(57) **CLAIM**

The ornamental design for a display screen with icon, as shown and described.

DESCRIPTION

FIG. 1 is a front view of a display screen with icon showing my/our new design;

FIG. 2 is a front view of a display screen with icon showing an alternative embodiment of the new design; and,
FIG. 3 is a front view of a display screen with icon of FIG. 2 shown on a device.

The broken line showing of the remainder of the user interface and the display screen is for environmental purposes only and forms no part of the claimed design.

1 Claim, 3 Drawing Sheets

FIG. 1

FIG. 2

FIG. 3
